UNITED STATES PATENT OFFICE.

ADELARD COUTURE, OF WARREN, RHODE ISLAND.

OIL BURNER.

Application filed July 28, 1923. Serial No. 654,426.

To all whom it may concern:

Be it known that I, ADELARD COUTURE, a citizen of the United States, residing at Warren, in the county of Bristol and State of Rhode Island, have invented new and useful Improvements in Oil Burners, of which the following is a specification.

This invention relates to certain new and useful improvements in oil burners and the primary object of the invention is to provide means for automatically effecting stoppage of the oil supply to the burner upon failure of sufficient supply of current to effect proper operation of the motor.

15 A further object of the invention is to provide means for causing initial manual starting of the motor and then further manual operation to set the motor for automatic stoppage in event of the current failure.

20 A still further object of the invention is to provide improved means for feeding the oil to the burner and for effecting consumption with maximum heat and for also utilizing the oil to lubricate the various moving parts of the apparatus.

25 Another object of the invention is to provide an improved oil burner structure and air feeding and diverting means therefor.

In the drawings:—

30 Figure 1, is a top plan view of the invention;

Figure 2, is a side elevation, partly broken away;

Figure 3 is an enlarged section on line 5 3—3 of Figure 1;

Figure 4, is a top plan view of the interior of the governor and electrical control device;

Figure 5, is an enlarged section on line 40 5—5 of Figure 1.

In proceeding in accordance with the present invention a base or bed 1 is employed and upon which the invention is mounted, including a motor 2, and a housing 3 for the governor and electrical control device, a rotary pump 4 being connected to the housing 3. A drive shaft 5 is driven by the motor and has a governor 6 mounted thereon, (Fig. 4.) A worm gear 7 is mounted on the drive shaft 5 and meshes with a worm gear 8 on a vertical shaft 9, the latter being mounted in ball bearings 10 and 11 carried by a burner casing 12.

The casing 12 is hollow and formed to 55 receive oil in which the worm gears 7 and 8 are submerged, the oil level being indi-

cated at 0 and controlled by an overflow pipe 13.

A fan 14 is mounted on the shaft 9 and above the fan is located a cup-shaped air diverter 15, the latter being stationarily secured within the casing top 12' of the burner and having a peripheral series of spaced inclined blades or plates 15a extending between the rim of the diverter and the walls 65 of casing top 12. A perforated plate 16 is carried by the shaft 9 and is located above the air diverter 15. A vertical pipe 17 has a discharge 18 from which latter oil drips onto the plate 16, the pipe 17 having a horizontal part 19 connected to the pump 4. The oil after passing through the pump is controlled by a valve 20, the stem 22 of which is connected to a diaphragm 23 and is tensioned by a coil spring 24, all of the 70 parts being mounted in a casing 25, the latter having a steam pipe 26 leading from the boiler (not shown) into the upper end of the casing above the diaphragm.

The oil of the burner is also utilized to lubricate the movable parts and accordingly, and as shown in Figure 3 a conducting pipe 27 conveys the oil into the retaining cup 28 of the ball bearing 11, from which the oil 85 gravitates into the lower part of the burner casing 12, where the oil is maintained at the level 0 by the overflow pipe 13.

A pressure valve 25' located in the pipe 19 also controls the oil after it passes the 90 pump 4, and is connected by a branch 21 to the overflow pipe 13. A pipe 50 conducts oil from the overflow pipe 13 to the motor housing 3.

The motor control switch is shown in 95 Figure 4 and includes a feed wire 30, and a switch 31, which latter in one position contacts with point 32 which connects to a wire 33 leading to the motor and from the latter the current passes out through a wire 100 34, thus causing operation of the motor. Upon throwing of the switch 31, to contact 35, the current will be diverted and will pass from the wire 30 and through a wire 36 to a spring arm 37 and through a conductive 105 disk 38 connected to the governor 6. From the disk 38, the current passes to a spring arm 39, the latter connected by a wire 33 to the motor. The disk 38 assumes a position in engagement with the spring arms 110 37 and 39, when the normal speed of the motor causes the governor 6 to move the

disk to the position depicted in Figure 4 of the drawings.

The casing 12' has air inlets 40 located beneath the fan.

5 In operation, the switch 31 is first turned to engage contact 32 to cause the current to flow through the motor 2 by passing through the wire 33, setting up operation of the governor, and thereby causing disk 38 to engage contact fingers 37 and 39, after which the switch is turned to divert the current so that it passes through the disk of the governor in passing through the motor. Should therefore, for any reason, the electric 15 supply be cut-off, the disk, will, due to the inoperation of the motor move out of engagement with the contact fingers 39 and 37 and cannot be again started except through manual movement of the switch, as above 20 described.

The operation of the motor, effects rotation of the shaft 9 and thereby fan 14, which causes air to be drawn into the burner casing 12' through the ports 40, the air then 25 passing upwardly between the diverter blades and being forced through the perforations of the plate 16, and at the same time operates the oil pump 4 to cause a flow of oil to the burner and to the bearings as 30 described.

Having thus described my invention, what I claim as new and desire to secure by Letters Patent is:—

1. In an oil burner, a casing having air 33 inlets, a horizontal fan above the inlets, a stationary air diverter device located above the fan, a horizontal rotary perforated plate above the air diverter, means to rotate the fan and plate, and means to supply oil to 40 the top of the plate, said air diverter device including a peripheral series of spaced plates extending in a substantially vertical plane and disposed between the periphery of the air diverter and the walls of the casing.

2. In an oil burner, a casing having air 50 inlets, a fixed air diverter in the casing, spaced blades between the diverter and the inner face of the casing forming substantially vertical passages open at their upper and lower ends, a rotary perforated oil receiving member above the diverter and blades, and a fan beneath the diverter, means to supply oil to the top of the oil 55 receiving member, and means to rotate the fan and said member.

3. In an oil burner, a casing having air

inlets, a fixed air diverter in the casing, spaced curved blades between the diverter and the inner face of the casing forming 60 substantially vertical passages open at their upper and lower ends, a rotary perforated oil receiving member above the diverter and blades, and a fan beneath the diverter, means to supply oil to the top of the oil 65 receiving member, and means to rotate the fan and said member.

4. In an oil burner, oil burner means including a rotary member, an electric motor for driving said member, a governor operated by the motor, a source of electrical supply, manual control means for the motor, means to electrically connect the source of supply to the motor, governor and said manual means whereby upon initial movement of said manual means in one direction the latter will pass the current directly through the motor to start same and upon a second movement in a different direction will subsequently divert the current to cause same to pass through the governor and then the motor and means whereby upon failure of the current supply the governor will break the electrical connection to the motor and stop the latter thereby to require said 85 initial movement of the manual means to restart the motor.

5. In an oil burner, oil burner means including a rotary member, an electric motor for driving said member, a governor operated by the motor, a source of electrical supply, a switch for the motor, means to electrically connect the source of supply, the motor, governor and said switch whereby upon initial movement of said switch in one direction the latter will pass the current directly through the motor to start same and upon a second movement in a different direction will subsequently divert the current to cause same to pass through the governor 95 and then the motor, and means whereby upon failure of the current supply the governor will break the electrical connection to the motor and stop the latter thereby to require said initial movement of the switch to 100 restart the motor.

In testimony whereof I have signed my name to this specification in the presence of two subscribing witnesses.

ADELARD COUTURE.
